UNITED STATES PATENT OFFICE.

FRANK M. ARCHER, OF BROOKLINE, MASSACHUSETTS.

DESIGN FOR CANDY.

60,637.

Specification for Design. Patented Mar. 21, 1922.

Application filed April 26, 1921. Serial No. 464,698. Term of patent 14 years.

To all whom it may concern:

Be it known that I, FRANK M. ARCHER, a citizen of the United States, residing at Brookline, in the county of Norfolk and State of Massachusetts, have invented a new, original, and ornamental Design for Candy, of which the following is a specification, reference being had to the accompanying drawing, forming part hereof.

The figure is a plan view of a piece of candy, constituting my new design.

I claim:

The ornamental design for candy as shown:

Signed at Boston, Massachusetts, this 25th day of April, 1921.

FRANK M. ARCHER.
